UNITED STATES PATENT OFFICE.

HERMAN FRASCH, OF CLEVELAND, OHIO, ASSIGNOR TO THE AMERICAN CHEMICAL COMPANY, OF WEST BAY CITY, MICHIGAN.

PROCESS OF AND APPARATUS FOR MAKING SODIUM CARBONATE BY AMMONIA.

SPECIFICATION forming part of Letters Patent No. 363,952, dated May 31, 1887.

Application filed October 19, 1882. Serial No. 74,614. (No model.)

To all whom it may concern:

Be it known that I, HERMAN FRASCH, a citizen of the United States of America, residing at Cleveland, in the county of Cuyahoga and State of Ohio, have invented certain new and useful Improvements in Processes of and Apparatus for the Manufacture of Sodium Carbonate by Means of Ammonia, of which the following is a specification.

10 This invention has reference more particularly to the manufacture of carbonate of soda or sodium carbonate from the natural brine of springs or wells, but is applicable to the manufacture of carbonate of soda from other brine 15 or solution of common salt, (sodium chloride.)

The brine or solution of sodium chloride ($NaCl$) is saturated with ammonia, (NH_3), and the saturated solution is treated with carbonic acid or carbonic dioxide, (CO_2), which, in connection with the ammonia and water, effects a decomposition of the sodium chloride and the production of bicarbonate of soda or hydrogen sodium carbonate ($HNaCO_3$) and of sal-ammoniac or ammonium chloride, (NH_4Cl). The bicarbonate of soda is separated by filtration from the ammonium chloride which remains in solution. The ammonia is recovered from the ammonium-chloride solution by distillation with lime (CaO) and reused. The bicarbonate of soda is roasted to convert it into carbonate of soda or sodium carbonate, (Na_2CO_3) and the carbonic acid that is expelled by roasting is utilized. This is the well-known ammonia-soda manufacture, which it is the object 35 of the present invention to improve in point of rapidity, economy, and efficiency of working. The invention comprises a new system of processes and apparatus, and also special improvements in the individual processes and 40 apparatus forming part of such system.

Heretofore the several operations have been carried on by successive batches, so to speak. For example, a given quantity of brine has been saturated with ammonia, this saturated 45 brine emptied into the carbonator, and a fresh quantity treated. In like manner each operation is successively performed on a given quantity or batch of material. In the present invention the operations go on mainly or entirely in a continuous manner, a constant

stream of material flowing through the apparatus and undergoing the necessary treatment in its passage. As heretofore carried on, also, the manufacture has been attended with a considerable loss of material or power, which is 55 saved by the present invention.

In the manufacture of soda from natural brines the methods of purification heretofore employed have been insufficient for the purpose, and the apparatus has in consequence 60 been liable to become choked with the impurities, (mainly the earthy chlorides, magnesium chloride, and calcium chloride.) In the present invention difficulty from this cause is avoided. The chlorides and other impurities 65 are so entirely removed that there is no interference with the progress of the manufacture.

The processes and apparatus forming part of the new and improved system may, for convenience, be considered under separate headings or in sections, as follows:

1. *The purification of the brine.*—This is accomplished by precipitating the impurities and separating the precipitate by filtration under pressure by means of the filter-press, 75 centrifugal filter, or equivalent apparatus. As already stated, the main impurities of natural brines are the earthy chlorides. Their precipitation is best effected by treating the brine first with magnesium carbonate, to precipitate the calcium as calcium carbonate, and then, after separation of the latter, with sodium carbonate to precipitate the magnesium as magnesium carbonate. This mode of precipitation has advantages over a single precipitation with sodium carbonate, both because the magnesium compound is obtained in a condition better adapted for use, being separate from the calcium compound, and because the brine is more readily cleared of the precipitate. When sodium carbonate is used, at once a double carbonate of calcium and magnesium forms, which takes a long time to precipitate, and which it is very difficult to get rid of. It is obvious, however, that filtration under pressure may be applied to brine treated at once with sodium carbonate, or to brine from which precipitation of impurities is effected in any suitable manner—as, for example, by treatment with lime, (calcium oxide, CaO), fol- 85 90 95 100

lowed by sodium carbonate. In case the brine contains iron, it is preferable to first precipitate it with a small quantity of lime, so that it will not contaminate the precipitated earthy carbonates.

- 5 *II. Utilization of the purified brine.*—The brine is made to absorb and recover ammonia from waste gases, and is afterward saturated with ammonia in the saturator. Preferably a part 10 (about ninety per cent.) of the brine is run into the saturator for saturation with ammonia, the remainder being used first in a wash-tower as a solvent or wash liquid to recover the ammonia from the waste gases, and afterward 15 added to the larger body of brine beyond the saturator. The recovery of the ammonia from waste gases by the larger body of brine is effected in column-tanks, through which said body passes on its way to the saturator.
- 20 The same gases are afterward washed with the smaller quantity of brine in what will herein-after be called the "square tower." The brine is or may be used to wash other gases containing ammonia.

- 25 *III. Saturation of the brine with ammonia.*—This saturation is effected in a continuous manner by agitating and spraying the current of brine in an atmosphere of ammonia that is constantly renewed. To this end the brine is 30 run through tubes wherein are spraying or agitating devices, and a current of ammonia is passed through said tubes in the opposite direction. The spraying or agitating devices preferred are revolving paddles scoop shaped 35 so as to lift the liquid. The tubes are preferably also set horizontal, and the flow of material is assisted by conveyer flights or wings set obliquely on the paddle-shaft. These flights or wings aid the paddles in agitating 40 and spraying the liquid. A cooling medium is employed to carry off the heat generated by the absorption of the ammonia.

- 45 *IV. Combination of the saturator with ammonia-still, with saturator-column, and with wash-tower, and the production of circulation through said apparatus.*—The inlet for the ammonia into the saturator is connected with the ammonia-still. (Hereinafter described.) The outlet is connected with the saturator-column, in 50 which it is passed through a body of the incoming brine, and it is also connected through said column and a pipe with a wash-tower. A vacuum maintained in the top of the wash-tower causes the circulation of the ammonia. 55 A single vacuum thus relieves the internal pressure in the still and causes the ammonia to flow through the saturator and saturator-column and to be delivered into the wash-tower. This tower, which will, for convenience, be called the "pipe-tower," is supplied with pure water, and the ammonia taken up is recovered by distillation. The vacuum is best maintained by means of an ejector or aspirator operated by a steam-jet.

- 60 *V. Correcting or rectifying the ammoniated brine.*—The brine, even if at first saturated with salt, (as it preferably is,) is no longer so when

it leaves the saturator, for it has become weakened through the condensation of water vapor which is carried from the still with the ammonia. In order to restore its strength the brine is passed through a column of solid salt, which it leaves saturated with sodium chloride. In passing through the saturator the brine is made to absorb an excess of ammonia, 75 and even after it leaves the salt column the absorbed ammonia will ordinarily be more than is required to effect the conversion of the dissolved sodium chloride into bicarbonate of soda. The strength in the ammonia is therefore reduced to this proper degree by addition of fresh brine. For this purpose the wash-brine, (referred to in Section II,) which contains only a small quantity of ammonia, is used. The vessels in which the admixture of 80 the ammoniated and the fresh or wash brine is effected will be hereinafter termed "averaging tanks." This superammoniation of the brine and the subsequent reduction to the standard strength is considered a new and important improvement, so, also, the restoration 85 of the saline strength of the brine after ammoniation.

90 *VI. Treatment of ammoniated brine with carbonic acid.*—The treatment with carbonic acid for effecting the formation of bicarbonate of soda, which precipitates, and of ammonium chloride, which goes into solution, is carried on continuously, the apparatus employed being in some respects like the saturator, but differing 95 in others. It is well known that the reactions between the sodium chloride, water, ammonia, and carbonic acid take place best with the carbonic acid under pressure and by means of intimate and repeated contacts of the 100 reagents. In the present invention the best conditions are secured without the numerous high columns heretofore employed, and with a great saving in space, power, time, and material. The vessels or tubes in which the carbonation of the ammoniated brine and precipitation of the bicarbonate of soda take place 105 are filled to a certain height with the ammoniated brine, (the level being maintained constant by overflow-pipes,) and the upper part 110 of the tubes are filled with carbonic acid under pressure. Buckets carried by shafts are revolved in the tubes, being alternately lifted above and carried through the liquid. When 115 they are lifted, they become filled with carbonic acid, which they carry down and deliver in the ammoniated brine. A very large number of vessels or tubes connected in series 120 may be employed. The ammoniated brine is allowed to flow in one direction and the carbonic acid in the other through the apparatus.

125 *VII. Production and maintenance of pressure in the carbonating or precipitating apparatus.*—The carbonic acid is preferably forced into this apparatus by means of compressors operated by steam-jet and acting on the principle of the injector. The outgoing gases from the carbonating or precipitating apparatus are made to force their way through a column of

liquid having a height sufficient to maintain the desired pressure in the carbonating apparatus, and the outlet of the liquid is controlled by an automatic relief-valve loaded to the desired pressure. The column is divided among 5 a series of column-tanks, instead of having it in one vessel. These column-tanks are supplied with the purified brine on its way to the saturator, as described in Section II. The ammonia, which is carried off in greater or less 10 quantities with the outgoing gases, is collected or absorbed by the brine, and so much less quantity is therefore required in the saturator. These gases pass from the column-tanks to the 15 square wash-tower, (indicated in Section II,) and may then, with very small loss, be allowed to escape.

VIII. *Production of carbonic acid.*—The supply of carbonic acid is mainly derived from 20 the calcination of limestone (calcium carbonate) in a kiln. The gaseous products from ordinary limekilns burning coal or wood are very impure, and should undergo a purifying operation before used in the carbonator or precipitating apparatus. To obtain the gases in 25 a state fitted for such use without expensive purification, a kiln burning petroleum or hydrocarbon oil, or similar clean fuel, is employed. It is not new to burn lime with such fuel, but 30 it is new to employ it for the production of carbonic acid in the ammonia-soda manufacture, and it is also new to combine with the kiln burning oil the necessary means for controlling production and for collecting the gases. 35 The kiln is arranged so that the carbonic acid is generated in a continuous manner. Besides the limekiln gases, carbonic acid is supplied from roasting the bicarbonate of soda, as hereinafter described.

40 IX. *Combination of carbonic-acid generators with carbonating or precipitating apparatus and utilization of heat of carbonic gases.*—As the carbonic-acid and other gases from the limekiln are very hot, and as a high temperature 45 is not desirable in the carbonator or precipitating apparatus, it is necessary to cool the said gases before admission into said apparatus. To effect this, and at the same time utilize the heat of the gases, the latter are 50 forced through flues or pipes of a grainer or apparatus for evaporating brine, so as to precipitate the salt through the heater—for example, of the grainer described in my application for graining and crystallizing salt, &c., 55 filed August 29, 1882, and numbered 70,569.

(Patented May 8, 1883, as No. 277,418.) The gases are further cooled and are deprived of a portion of their moisture by passage through a condensing apparatus. To force the gases 60 through the apparatus, the compressors referred to in Section VII are employed. The carbonic acid from the roasting apparatus is forced by a compressor through a condenser and is delivered into the kiln-gases as they 65 pass to the carbonating or precipitating apparatus. The condenser collects some ammonia from the carbonic acid. The carbonating or

precipitating apparatus is therefore connected with the kiln and roaster through apparatus for compressing, cooling, and drying the gases 70 and for recovering waste energy or material therefrom.

X. *Separation of the precipitated bicarbonate of soda from the ammonium chloride solution.*—A continuous filter is employed, the bicarbonate 75 being collected on an endless traveling belt of filtering material, whereon it is washed and whereby it is delivered to conveyers which carry it to the roasting apparatus. The filtering-belt travels over an open-work or perforated support, under which a vacuum is maintained. The chloride-of-ammonium solution passes through the belt and its support and is collected in a tank, called herein the "spider" tank. 80

XI. *Recovery of ammonia given off at filter and production of vacuum in latter.*—More or less air makes its way into the tank beneath the filtering belt, wherein the vacuum is maintained. This air carries along with it some 90 ammonia, which is recovered in a wash-tower (called herein the "iron-tower") supplied with fresh water. The vacuum is produced by an aspirator or steam-ejector between the filter-tank and the bottom of the tower. The wash-water is supplied to the ammonia-chloride tank. 95

XII. *Roasting of bicarbonate of soda to convert it into carbonate.*—The roasting is performed in a continuous manner. The bicarbonate is carried through flues heated to a high temperature, wherein it is continually agitated, so as to maintain it in a granular condition, and thus to permit the escape of the moisture and carbonic acid and ammonia. To secure the 100 necessary conveyance and agitation, scoop-paddles and conveyer-flights, keyed to a central shaft and arranged to alternate thereon, are employed. The adoption of these means is the result of a long series of experiments, 105 great difficulty being found in preventing caking of the material, which not only causes imperfect working, but is soon followed by the stoppage of the apparatus. To secure the necessary high temperature, the flues are exposed 110 to the direct fire heat and to the direct impact of the products of combustion. Loaded flaps permit the introduction of the material into the flues and its removal therefrom without allowing inflow of air. An outlet-pipe connected with the first tube of the series carries 115 off the disengaged gases. 120

XIII. *Recovery of fine dust from roaster and of ammonia and utilization of the carbonic acid.*—As the disengaged gases leave the roaster they 125 carry with them fine particles of sodium carbonate and bicarbonate. These particles are collected in a dust-trap, which is supplied with a current of pure water for absorbing and carrying away the ammonia. The end of the 130 outlet-pipe from the roaster dips below the surface of the water in the dust-trap, so that the gases must pass through said water, which collects the dust and absorbs a large part of

the ammonia. The water is constantly renewed, and is kept at the same level by means of an overflow. The soda dust and the ammonia are carried off with the water to the still.

5 The carbonic-acid and other unabsorbed gases pass on to a compressor, that forces them into the carbonating or precipitating apparatus. Between the compressor and the carbonating or precipitating apparatus is a small surface-
10 condenser, which removes moisture and any remaining ammonia. The use of the dust-trap not only saves the fine particles, but prevents them from clogging other parts of the apparatus.

15 **XIV. Conveying, cooling, and packing the carbonate of soda.**—The carbonate of soda leaves the roaster as a dry granular material, very hot, nearly or quite red-hot, in fact. It is conveyed to a packing apparatus of any known 20 or suitable construction by a screw-conveyer, and is cooled during its passage by a water-jacket surrounding said conveyer.

25 **XV. Collection of ammoniated liquors for distillation.**—The receptacle from which the still is supplied will be called the "ammonium-chloride tank." Into it the various wash-waters, &c., containing ammonia (excepting always the wash-brine which is used in the averaging-tanks) are pumped. The liquids are the wash-
30 water from the pipe-tower, Section IV, the overflow-water from the dust-trap, Section XIII, and the water from the surface condenser, Section XIII. The chloride-of-ammonium solution from the spider-tank below 35 the filter is also pumped thereinto.

40 **XVI. Distillation of ammoniated liquors.**—The distillation is performed in a continuous manner. The liquors are mixed with milk of lime and flow through one or more still-columns into a boiler, into which steam is admitted. The ammonium chloride is decomposed by the action of the lime and heat (calcium chloride being formed) and the ammonia is expelled by the heat from solution. The ammonia as it 45 escapes is made to heat the incoming liquors, whereby it is not only cooled, but also deprived of some of the attendant moisture. A condenser is also employed to further cool and dehydrate the ammonia before permitting it 50 to pass to the saturator.

45 **XVII. Utilization of ammonia naturally present in the brine.**—Some natural brines contain ammonia. This ammonia, in case the brine is to be evaporated for salt, is recovered by boiling the brine with lime, as just described, and is utilized in the saturator.

55 There are many minor points of invention—such as particular construction or combination of parts—in the apparatus which form part of the present improvement. They are herein-after fully set forth.

60 The accompanying drawings represent apparatus constructed in accordance with the invention and adapted to use in carrying the improved processes into effect.

65 Figure 1 is a vertical section, partly in elevation, of the column-tanks; Fig. 2, a vertical

longitudinal section, partly in elevation, of the saturator and is connected wash-tower (pipe-tower); Fig. 3, an end view of saturator; Fig. 4, a cross section and a sectional elevation, on an enlarged scale, of one of the saturator-tubes; Fig. 5, a vertical section of salt-column; Fig. 6, a vertical longitudinal section, partly in elevation, of the carbonating or precipitating apparatus; Fig. 6*, a vertical section of trap to be used in place of the pressure-valve shown in Fig. 6; Fig. 7, a cross-section of a tube in said carbonating or precipitating apparatus; Fig. 8, an end view showing a zigzag arrangement of tubes; Fig. 9, a vertical section of carbonic-acid generator or lime-kiln; Fig. 10, a horizontal section, and Fig. 11, a detail view in sectional elevation of the same; Fig. 12, a vertical section of the condenser between the grainers and carbonator or precipitating apparatus; Fig. 13, a vertical longitudinal section, partly in elevation, of the filter or apparatus for collecting the precipitated bicarbonate of soda; Fig. 14, an end view, and Fig. 15, a partial cross-section, of the same; Fig. 16, a vertical longitudinal section, partly in elevation, of the roaster and its dust-trap; Fig. 17, a vertical cross section of roaster; Fig. 18, a vertical longitudinal section of apparatus for conveying and cooling the carbonate of soda; Fig. 19, a vertical section, partly in elevation, of the ammonia-still, the view being divided to accommodate the sheet; and Fig. 20, a partial side elevation of one of the boilers forming part of the still. Fig. 21 is a diagram illustrating the whole plant or connected apparatus in plan view.

The column-tanks, Fig. 1, comprise a number of vessels, A A' A'', each provided with a perforated false bottom, a , a gas-inlet pipe, a' , communicating with the space beneath said false bottom, a gas-outlet pipe, a'' , communicating with the upper part of the vessel, a liquid-inlet pipe, a^3 , emptying into the upper part of the vessel, and a liquid-outlet pipe, a^4 , at such distance above the bottom as it is desired to have the liquid stand. The gas-outlet a'' of the lowermost vessel, A'', is connected with the gas-inlet a' of the next highest vessel, A', and the gas-outlet of the latter with the gas-inlet of the vessel A. The liquid-outlet a^4 of the upper vessel, A, is connected with the liquid-inlet a^3 of the next vessel, A', and the liquid-outlet of this vessel with the next one, A''. The vessels are thus connected in series, so that the liquid and gas will flow through them in opposite directions, the gas being made to pass through the liquid successively in each vessel.

The liquid introduced into the vessel A will fill that vessel to the height of the outlet-opening, will overflow into the next vessel, A', partially fill it, and overflow into the lower vessel, A'', and will escape by the outlet a^4 of the latter. The gas introduced by the inlet a' of the lowermost vessel will be delivered beneath the perforated false bottom a of that vessel, will bubble up through the liquid therein, be-

ing diffused by the perforations in the false bottom, will pass through the outlet-pipe a^2 , will be delivered below the false bottom a of the next vessel, A' , by the inlet-pipe a' thereof, will bubble through the liquid therein, will pass into and through the liquid in the top vessel, A , and will finally escape by the outlet a^2 of the latter. Bends or traps a^5 in the pipes connecting the liquid inlets and outlets prevent the gas from passing through said pipes, and thus from passing through the tubes, without bubbling through the liquid.

The pressure required to deliver the gas below the false bottom of the lowest vessel is proportionate to the heights of all the columns added together. The three columns act as one column of triple height in maintaining the pressure in the vessel (carbonating or precipitating apparatus) connected with the gas inlet of the lower vessel, and the useful effect of a high column is obtained without the inconveniences attending its use. Moreover, by the division of the column the gas is more thoroughly washed and the soluble matter (ammonia) dissolved out.

The saturator, Figs. 2, 3, 4, comprises a frame, B , a series of connected tubes, B' , a jacketing-vessel, B^2 , a shaft, B^3 , extending through each tube, a number of scoop-paddles, b , and conveyer-flights b' on each shaft, a train of gears, b^2 , a driving-pulley, b^3 , a liquid-inlet, b^4 , and a gas-outlet, b^5 , for the upper tube, and a gas-inlet, b^6 , and liquid-outlet b^7 for the lower tube.

B^4 is a collecting-vessel for receiving the liquid (ammoniated brine) from the saturator; B^5 , the saturator-column through which the liquid (brine) passes on its way to the saturator, and B^6 the wash-tower (pipe-tower) in which the gas escaping from the saturator-column is washed to recover the ammonia.

The scoop-paddles b and conveyer-flights b' are arranged to alternate on the shaft, and are set spirally around the same. The several shafts are connected and revolved by the train of gears b^2 , to which motion is imparted by a belt or pulley, b^3 .

The gas (ammonia) admitted by the inlet b^6 passes successively through the tubes B' in the direction of the arrows, Fig. 2, and the liquid (brine) passes in the opposite direction. The liquid is constantly lifted and showered by the paddles, and the showered liquid, being struck by the paddles and conveyer-flights, is dashed into spray, which spray is advanced by the action of the conveyer-flights. The tubes being filled with an atmosphere of gas, which is constantly being renewed, the absorption of the ammonia is rapid and complete. The liquid (ammoniated brine) is finally collected in the vessel B^4 , and is thence pumped through the salt-column into the averaging-tanks.

The saturator-column B^5 is constructed like one of the column-tanks, Fig. 1, and the gas escaping by the outlet b^5 is made to bubble up through the brine in said column. The latter not only collects and absorbs ammonia from

the escaping gas, but also maintains a certain pressure of gas in the saturator.

The wash-tower B^6 is or may be of an ordinary or suitable construction; but is preferably a plain pipe filled with coke or similar material, and provided at the bottom with a gas inlet, b^8 , and liquid-outlet b^9 , and at the top with a liquid-inlet, b^{10} . An aspirator or ejector, b^{11} , is arranged to create a vacuum in the top of the tower. This vacuum is sufficient to cause the circulation of the gas through the saturator, saturator-column, and pipe tower. In the tower the gas meets the stream of water that trickles over the coke, and the last traces of ammonia are absorbed thereby. It will of course be understood that the absorption of ammonia in the saturator and saturator-column tends to create a vacuum, and that the amount of gas exhausted by the aspirator or ejector b^{11} is very small. The jacketing-vessel B^2 has an inlet-pipe, b^{12} , that delivers the cooling medium (water) at the bottom of the vessel, where the heat of absorption is greatest, and an outlet-pipe, b^{13} , that allows the heated liquid to run off at the top.

The salt-column, Fig. 5, comprises a containing-vessel, C , having a hopper-mouth, C' , for admitting the salt, a valve, C^2 , for closing said mouth, when required, to prevent escape of ammonia, a perforated false bottom, C^3 , for the salt to rest upon, a perforated inlet-pipe, C^4 , for admitting the liquid (ammoniated brine) and spraying it over the salt, and an outlet-pipe, C^5 , for carrying off the liquid. This outlet is provided with a glass tube, C^6 , for indicating the level of liquid in the vessel C .

The averaging-tanks are large receptacles, into which the superammoniated brine and the fresh brine are pumped or fed by gravity from a higher level. Preferably the fresh brine is delivered into the tanks with and the supply is regulated by turning cocks in the different pipes, so that a greater or less proportion of fresh brine will be admitted as the liquid in the averaging-tanks shall show an excess or lack of ammonia. The averaging-tanks are or may be provided with level-indicators and with a mixing apparatus—such, for example, as a perforated pipe for delivering compressed air into the liquid to agitate the same. Two or more tanks are preferably used, each being in its turn filled to the proper height and then discharged.

The carbonating or precipitating apparatus, Figs. 6 and 7, comprises a frame, D , a number of vessels or tubes, D' , connected with each other in series by gas-conveying pipes d and liquid-overflow pipes d' ; and in each vessel or tube a series of buckets, D^2 , carried by a revolving shaft, D^3 , together with suitable inlets and outlets for the gas (carbonic acid) and liquid, (ammoniated brine,) with means for cooling or regulating the temperature in said tubes and with gearing for revolving the shafts. The buckets are preferably cast, and are bolted at the bottom to arms attached to bosses that are keyed to the shaft, as shown

clearly in Figs. 6 and 7. The gearing shown consists of sprocket-wheels and chains; but any other suitable system could be used instead. The precipitating vessels or tubes D' are inclosed in a jacket forming part of frame D, and a perforated pipe, d^x, is provided, by which water or other suitable liquid may be sprayed on the top vessel or tube and allowed to run over the others, so as to preserve the proper temperature in the interior.

The liquid to be treated with carbonic acid (ammoniated brine from the averaging-tanks) is introduced into the apparatus by the inlet d², fills the upper vessel or tube D' to the height 15 of the overflow d', then runs into the next vessel or tube, overflows into the next, and so on, till finally it escapes through the overflow-pipe d' of the bottom vessel or tube. The gas (carbonic acid) is introduced under pressure 20 into the bottom vessel or tube D' by the inlet d³ and fills the several vessels or tubes above the liquid. The shafts B³ revolve so as to carry the bucket's mouth forward, as indicated by the arrow, Fig. 7. As the buckets revolve 25 they carry down in their descent the carbonic acid, which they deliver below the surface of the liquid. They then become filled with liquid, which, as they rise, they lift and then pour out through the atmosphere of carbonic acid. 30 Thus they bring the compressed carbonic acid repeatedly into intimate contacts with the ammoniated brine, and the result is the decomposition of the sodium chloride and the formation of ammonium chloride and bicarbonate of 35 soda.

The decomposition of the salt (sodium chloride) and precipitation of the bicarbonate begin in the upper vessel or tube and continue in the others, becoming practically complete 40 by the time the lowermost vessel is reached. The gas is allowed to escape through the column-tanks, Fig. 1, which maintain the desired pressure in the precipitating vessels or tubes D', while permitting a continuous flow. It is 45 obvious that the pressure is maintained in all the vessels or tubes equally, no matter how many of them there may be, and no extra power is therefore required to compress the gas anew for each vessel or tube. Twenty to 50 twenty-five of the precipitating vessels or tubes can be connected in series without any difficulty, and experience has shown the absorbing of carbonic acid so complete that the carbonic acid in the exit gases (after passing 55 through the tubes) may be reduced from one per cent. to one and one-half per cent. instead of ten per cent. or more, as has commonly been the case heretofore.

The gas in passing takes up ammonia from 60 the liquid, but it takes up most from the tube it first meets—to wit, the lowest tube in which precipitation is practically complete—and the abstraction of ammonia from it does no harm but will, on the contrary diminish the possible 65 loss of ammonia during the subsequent filtration. The size of the vessels or tubes D' is such as admits of a ready control of the tem-

perature at the point found most advantageous. Water or other suitable liquid at a suitable temperature is distributed by the perforated 70 pipe d^x over the top vessel or tube, flows over its exterior to the next vessel or tube, and so on over each vessel, until it finally escapes by the outlet d⁴.

The ammoniated brine is pumped into the 75 precipitating vessels or tubes D' against the pressure of the contained carbonic-acid gas. The outlet for the ammonium-chloride solution holding the precipitated bicarbonate of 80 soda in suspension is controlled by an automatic relief-valve, D⁴, of ordinary construction, which is properly loaded so as to permit the said solution and precipitate to flow away without disturbing the conditions of pressure 85 in the apparatus.

Instead of a relief-valve, the trap shown in Fig. 6^a may with advantage be employed. It may be considered, generally, as a U or siphon trap having legs of sufficient length to maintain the pressure in the precipitating apparatus, and provided with stirrers to prevent 90 the bicarbonate from settling. The inclosing vessel D⁵, which forms the descending leg of the siphon, is provided with a screw or propeller, d⁷, carried by a vertical shaft, d⁸, and 95 placed near the bottom of the vessel. The pipe D⁶, which forms the ascending leg, is provided with an upright stirrer, D⁷, the shaft of which is stepped in a skeleton frame, d⁹, at the bottom of said pipe D⁶. 100

In Fig. 8 the precipitating tubes or vessels D' are arranged in a zigzag instead of in a vertical line, whereby a larger number can be placed in the same height.

Since the overflow-pipes d' are no longer 105 vertical, there is greater liability of the precipitated bicarbonate clogging the tubes, and it is advisable, therefore, to provide each overflow-pipe d' with a stirrer like that illustrated in Fig. 6^a and lettered D', the said stirrer being, however, inclined to correspond with the position of the overflow-pipe in which it is placed. Each vessel or tube is shown provided with a perforated pipe, d^x, for distributing water over it. The water is collected by inclined 110 shelves d⁵, and carried off by troughs at the bottom thereof.

The carbonic-acid generator or limekiln, 115 Figs. 9, 10, and 11, comprises, in connection with a number of atomizers, E, a shaft, F, provided at the top with flues E', for collecting and carrying off the carbonic acid, and also with a direct outlet, E², and a removable cover, E³, therefor, and terminating at the bottom in an inverted cone, E⁴, the contracted mouth of which 120 has a grating, f, on which the lime may rest. The atomizers E are placed so as to deliver the fuel (petroleum or hydrocarbon oils) into the shaft F just above the cone E⁴. Each atomizer 125 comprises an oil-receptacle, e, an oil-delivery tube, e', and a steam-pipe, e². The oil-tube e' and the steam-pipe e² extend through the wall of the shaft F. The outside portion of the oil-tube is bent downward, so as to extend into 130

the oil in the receptacle *e*. The inner end, *e*², is bent upward, so that the jet from the pipe *e*² will pass over the delivery opening and will draw the oil from the receptacle *e* and spray it among the material in the shaft *F*. The receptacle *e* being below the delivery opening, no oil will go into the shaft except what is drawn up by the steam-jet. The air to support combustion enters through the grate *f*. Connected with the flues are the compressors, in the form of injectors, which take the gas from the flue *E'*, force it through the grainers and condensers, (shown in Fig. 12,) and delivers it in a compressed state into the carbonator or precipitating apparatus, Figs. 6 and 7 or Fig. 8.

The action of the compressors during operation gives ordinarily sufficient control over the draft of the kiln; but a valve, *f'*, sliding in guides below the grate *f*, is also provided as an additional or auxiliary means of regulation or means to be used when the compressors are not in action. The cover *E'* is removed to fill the shaft with limestone and to supply additional limestone from time to time. The lime is removed from the bottom, as required, by removing one of the grate-bars. The grate is sufficiently elevated to allow a car for receiving the lime to be run beneath it. During operation the fuel delivered in regulated quantity is distributed all over the base of the shaft, so that all parts of the limestone are equally calcined. By regulating the draft the best temperature for working can be readily secured, and the supply of carbonic acid generated can be kept within the desired limits. The grainers may be of any ordinary or suitable construction, but are preferably such as described in my application already referred to.

The condenser, Fig. 12, through which the carbonic acid is passed on its way from the kiln to the carbonating or precipitating apparatus resembles a still-column in construction. It comprises a shell, *G*, divided by perforated diaphragms *G'*, and having overflow-tubes *G*² for conducting the condensing liquid from one diaphragm to the next. The liquid inlet *g* and gas outlet *g'* are at the top of the shell, the gas-inlet *g*² and the liquid-outlet *g*³ at the bottom. The gas (carbonic acid from limekiln) is forced into the shell *G* at *g*², and passes up through the perforated diaphragm *G'* and out at the top. The liquid (water) for cooling the gas and condensing the moisture therein, being introduced at *g*, descends from diaphragm to diaphragm by the overflow-tubes *G*², and, being prevented by the pressure of the rising gas from passing through the perforations, collects to a certain depth, regulated by the height of the overflow-tubes. The lower ends of the overflow-tubes dip into cups *g*⁴, which become filled with water and prevent the gas escaping up the said tubes. The gas in passing through the perforated diaphragm and the layers of water thereon becomes cooled and deprived, in part at least, of its moisture. The gas in the condenser being under pressure, it is necessary to control

the outflow of liquid. For this purpose the liquid-outlet *g*³ is connected with a trap, *H*, having two long but unequal legs, *h h'*. The longer leg, *h'*, projects above the outlet *g*³ or top of the shorter leg, *h*, to such a distance that the liquid therein will about balance the least normal pressure in the lower part of the condenser. The entire length of the longer leg is 75 such that the pressure of the liquid therein will always be greater than the pressure in the condenser. Variations in pressure in the condenser will therefore cause the liquid to rise and fall in the shorter leg, and the trap will 80 automatically adapt itself to such variations and continue to operate. It will never blow out, because the pressure will be insufficient to balance the column in the longer leg, *h'*, except when the shorter leg is wholly or partly filled 85 with liquid. In the longer leg, *h'*, at or about the level of the outlet *g*³, a stop-cock, *H'*, is placed, so that the liquid may be drawn off from the higher portion of the longer leg and be blown off from the V-shaped part of the 90 trap.

*H*² is a waste-water funnel and pipe.

The filter, Figs. 13, 14, and 15, by which the precipitated bicarbonate of soda is separated from the ammonium-chloride solution, 95 comprises a filter-tank, *K*, an endless filter-belt, *K'*, and drums *K*², for supporting the belt, together with various accessory parts. The drums *K*² are journaled in bearings in a framework and the filter-belt, which runs thereon 100 and is moved by power applied to one or both drums, passes over the top of the filter-tank *K*, the said tank being placed between the drums, and has its top formed of rollers *k*, to diminish friction on the belt and to allow the filtered 105 liquid to fall into the tank. Above the tank is a trough formed by the side pieces, *k'*, the bottom of the trough being the top of the tank. The trough is somewhat narrower than the filter-belt, and at the front (left hand) ends 110 of the side piece are turning-up devices *k*², (shaped something like plowshares,) which raise the edges of the belt and give to it a trough shape. (See Fig 15.) A flap, *k*³, of stiff rubber, fits within the folded belt and 115 prevents the liquid which is introduced by the pipe *k*⁴ from running out, but does not interfere with the movement of the belt, which is in the direction of the arrows. The trough is closed by a cover, *k*⁵. An atomizer, *L*, is 120 arranged with the jet openings inside the cover in position to spray water over and to wash the bicarbonate on the filter-belt. A hinged evening device, *L'*, distributes the bicarbonate evenly over the bottom of the 125 trough. A vacuum is maintained under the filter-belt to assist the percolation of the liquid.

The tank *K* is divided by partitions *k*⁶ into a number of compartments, each connected by an individual branch pipe, *k*⁷, having a 130 cock, *k*⁸; and a common pipe, *k*⁹, with an aspirator and compressor, *K*³. This aspirator and compressor create a vacuum in the filter-tank below the filter-belt, and the air or gas

withdrawn is forced into a wash tower to recover the ammonia therefrom. The object of having an individual branch pipe and cock for each compartment is to enable the vacuum 5 to be independently controlled, so that different degrees of vacuum may be maintained therein. Over the first or left-hand compartment the liquid is deeper and the vacuum in the compartment beneath is kept correspondingly large, while there is only a very shallow layer of liquid, or none at all, over the right-hand compartment, and a small degree only of vacuum is requisite. Each compartment of the tank is also connected by an individual 10 branch pipe, k^0 , having a stop-cock, k^1 , with the common pipe k^2 , leading to a tank which collects the filtered liquid. (ammonium-chloride solution.) The pipe k^0 is connected with this tank, so that the pressure therein is relieved and does not interfere with the flow of liquid from the filter-tank.

The filter-belt carries the washed bicarbonate and delivers it into a conveyer, L^2 . Scrapers L^3 detach the bicarbonate which does not fall off of itself. The filter-belt is purposely left rather loose. One or more friction-pulleys—such as shown at L^4 —are used to prevent slipping on the drums. Said pulley, which is faced with rubber, has sliding journals, and is 25 pressed by screws l against the belt, so as to clamp it between itself and the drum. Slipping is thus prevented without tightening the filter-belt.

The roaster, Figs. 16 and 17, comprises, 30 mainly, a series of flues, M , set in a furnace, M' , and provided with internal agitating and conveying devices, M^0 M^1 . The agitating devices are scoop-shaped paddles M^2 , and they are arranged on shafts M^4 alternately with the 35 conveying devices or flights M^3 . The shafts are driven from a power shaft, m , by means of chains and sprocket-wheels. The material to be roasted (bicarbonate of soda) is introduced by the hopper m' , and the roasted material (sodium carbonate) is delivered at the 40 outlet m^2 . Both the hopper's mouth and the outlet are protected by loaded flap-valves m^3 for excluding air, while permitting the introduction and discharge of the material.

45 The furnace M' , as shown, is divided into several fire-chambers, each having its own fire-place n and discharge-flue n' , the discharge-flues delivering their products, however, into a common chimney or uptake.

50 The flues M , being placed in the fire-chambers, are exposed to the full heat of the fire, and, being surrounded by the products of combustion before they have a chance to cool and by being also exposed to direct radiation, 55 are highly heated. The heat expels the extra equivalent of carbonic acid, also the moisture and ammonia. The conveyer-flights propel the material through the flues and the paddles lift the bicarbonate and throw it over the flues, 60 and thus insure that all parts are equally roasted. The paddles also keep the mass in a granular condition, which permits the easy

escape of the gases to be driven off. The paddles are of the utmost importance, as a screw alone would roll and ball the soda, and the latter would collect in lumps fused on the outside and containing inside ammonia, moisture, and carbonic acid.

With the apparatus described a fine powder is produced perfectly free from ammonia and moisture. The expelled products are carried off by the pipe n^2 , the outer end of which dips below the surface of the water in the dust-trap N . The gases pass out by the pipe n^3 to the compressor, which forces them into the carbonating or precipitating apparatus, on their way to which they pass through a surface-condenser that condenses more or less of the moisture and recovers the ammonia which dissolves in the condensed water. The water in the dust-trap is constantly renewed through the pipe n^4 . The water collects the soda dust which may be carried out of the roaster by the gases, and also dissolves a portion of the ammonia. The water escapes by the overflow n^5 .

The sodium carbonate leaves the roaster by the outlet m^2 in the form of a fine dry powder, which is very hot. In the upper flues the temperature is kept low by evaporation or vaporization which takes place therein; but in the lower flues but little evaporation or vaporization takes place, and consequently the sodium carbonate is delivered of a temperature nearly equal to that of the fire-chamber. To convey it, the apparatus shown in Fig. 18 is employed. This consists, mainly, of a screw-conveyer, P , provided with a water-jacket, P' , whereby the soda is cooled in its passage. The conveyer P being at a higher level than the outlet of the 95 roaster, an elevator, P^2 , is employed to raise the material and deliver it into the conveyer. The elevator should be wholly of metal, or, at least, it should contain no inflammable material or material likely to be destroyed by the 100 high temperature of the powder. The conveyer delivers the cooled carbonate of soda to packing apparatus of ordinary or suitable construction, which packs it in barrels or other receptacles.

115 The still, Figs. 19 and 20, receives the ammonium-chloride solution from the filter, Fig. 13, also the water from the pipe-tower, Fig. 2, from the iron tower, from the dust-trap, Fig. 16, and from the surface-condenser, these liquids being first collected in the ammonium-chloride tank.

120 As shown, the still proper comprises the two columns Q Q' and the two boilers R R' , with their appendages. In connection with them are the small auxiliary condensing-column Q^2 , for cooling the ammonia and heating the incoming liquid, the condenser-coil Q^3 , for further cooling the ammonia and depriving it of moisture, the lime-tank S , for mixing the ammoniacal liquor with milk of lime, and the mixing apparatus S' .

125 The still-columns Q Q' are alike, and comprise each a hollow column of irregular form

inclosed in a shell or casing. The hollow column is formed of a number of communicating vessels, q , of a general hemispherical shape, fitted and held together by a bolt, q' , the flat sides being uppermost. The lowest vessel q has in the bottom holes through which communication is established between the interior of the hollow column and that of the inclosing casing or shell q^2 . Surrounding each vessel q , (except the top and bottom ones,) and resting upon the vessel q next in order below, are frusto-conical drip plates q^3 , the object of which is to direct upon the flat top of the next vessel q the liquid which may fall on said plates. The ammoniacal liquid to be distilled is admitted into the shell q^2 of the column Q by the pipe q^4 , flows over the exterior of the vessels q therein, passes the siphon-pipe q^5 into the shell of the column Q', flows over the exterior of the vessels therein, and finally runs out by the pipe q^6 , and is delivered into one of the boilers R R'. Steam and ammonia from the boiler pass up the pipe q^7 and into the top vessel q in the column Q'. They descend through the interior of said vessels, heating them and vaporizing the ammonia from the liquid flowing over the exterior, and escape at the bottom into the shell q^2 .

From the top of the shell q^2 of column Q' the steam and hot ammonia vapor pass by the pipe q^8 into the top vessel q of column Q; thence they descend through the interior of vessels q and escape at the bottom into the shell q^2 of column Q. The steam and ammonia thence escape by pipe q^9 into the condenser-column Q², of which more will be said hereinafter. The boilers R R' are both plain cylinders. They are provided each (see Fig. 20) with a steam-inlet pipe, $r^1 r^2$, extending the length of the cylinder and perforated at intervals, also with a blow-off pipe and cock, r^3 , with a steam and vapor outlet, $r^4 r^5$, and with a liquid-inlet pipe, $r^6 r^7$. The steam inlet pipes $r^1 r^2$ are connected with a common steam-pipe, s , and are provided each with a cock, $s^1 s^2$, respectively, whereby steam can be shut off or let on to each boiler independently. There are also cross connection-pipes $r^8 r^9$ between the steam inlet pipes $r^1 r^2$ and the steam and vapor outlets $r^4 r^5$, respectively, and each cross-pipe has a cock, $s^3 s^4$, respectively.

The steam and vapor outlet pipes $r^4 r^5$ are connected with the pipe q^7 , and have each a cock, $s^5 s^6$, respectively. By properly opening and closing the cocks the steam from pipe s can be admitted into either boiler. Then, with any ammonia vapor generated, it can be passed into the second boiler, and thence into the still-columns, or it can be passed directly into the still-columns without passing through the second boiler, or the steam can be passed through both boilers simultaneously, or the steam can be admitted directly into the still-columns without passing through either boiler. For example, by closing cocks $s^2 s^3 s^5$ and opening cocks $s^1 s^4$, and s^6 , the steam from s will pass through r , R, r^2 , r^3 , r^4 , R', r^5 , and q^7 to column Q'. By closing cocks $s^4 s^6$ and opening cocks s^5 (leaving $s^2 s^3$ closed and s^1 open) the route is the same, omitting r^7 , r^8 , R', and r^9 , the steam thus passing directly from pipe r^2 into the pipe q^7 . By opening cocks $s^1 s^2 s^5 s^6$ and closing $s^4 s^3$ steam from pipe s will pass into both boilers R R', and thence by the outlets $r^2 r^3$ to the pipe q^7 .

The liquid-inlet pipes $r^4 r^5$ are connected with the pipe q^6 , leading from the still-column Q, and they have each a cock, $s^7 s^8$, respectively, whereby the liquid can be directed into either of the boilers or be allowed to flow into both.

Ordinarily the liquid from the still-column is allowed to flow into one boiler—say R—while the steam is passing from pipe s into the other—say R'. The steam and vapor from the latter pass into the first boiler, R, thence to the still-column Q'. When the ammonia is all driven off from the liquid in boiler R', it is cut off by closing cocks $s^3 s^4$, ($s^4 s^6 s^8$ being already closed,) and the liquid is blown off through the cock r^8 . The exit can be assisted with steam from pipe s , if desired.

During blowing off the steam is admitted into boiler R, and passes thence directly into still-column. When boiler R' is empty, the cock s^7 is closed and cock s^8 opened, so that the ammoniacal liquid runs into the boiler R'. The cock s^4 is also opened and the cock s^5 closed, so that the steam and vapor from boiler R now pass through boiler R', and thence to the still-column. When the liquid in boiler R is exhausted, this boiler is blown off and the cocks are opened and closed to effect the proper change in the circulation.

The mixing apparatus S' consists of a vessel, t , in which is an upright shaft, t' , and one or more horizontal stirring-rakes, t^2 , carried by said shaft. The shaft t' is driven from the horizontal shaft t by the bevel-gears t^1 . Lime from the carbonic-acid generator or kiln, Fig. 9, is slaked in tubs close to said generator or kiln, and the milk of lime is delivered by means of montejus (such as commonly employed in sugar-works) into the mixing apparatus, which keeps a constant supply ready for delivery into the lime-tank S. As shown, the milk of lime is delivered through the pipe t , and the flow is regulated by the cock t^3 ; but it is preferred to place a measuring-elevator between the mixing apparatus and the lime-tank, so as accurately to regulate the delivery. More than one mixing apparatus can be used.

The lime-tank S is a horizontal cylinder, in which is centrally mounted a shaft, u , provided with stirrer-frames u' . Two such frames will answer; but a larger number can be used, if desired. The shaft is revolved by a belt on pulley u^2 , or by other appropriate gearing. The ammoniacal solution is delivered from the condenser-column Q² by the pipe u^3 , and passes into the still-column Q by the pipe q^4 .

The condenser-column Q² is not, *per se*, of novel construction. It consists of the upright shell v , perforated diaphragms v' , overflow-pipes v^2 , and cups v^3 . The steam and vapor

inlet pipe q^o is provided with a cap, v^t , which prevents the liquid from running through said pipe into the still-column. In the condenser-column the steam and hot vapor from the still-columns meet the incoming ammoniacal liquor (which is delivered in measured quantities through the pipe v^o) and parts with its heat thereto, so that the said liquor is hot when it enters the lime-tank S, wherein the decomposition of the ammonium chloride by the lime is effected. The lime-tank S may be heated by outside agencies, if desired; but this ordinarily is not necessary. In the condenser-column, also, the steam is condensed and the ammonia vapor partly deprived of moisture, both by contact with the liquid and by passing through the holes in the diaphragms v' .

The condenser-coil Q³ is a simple coil combined with a perforated pipe, v^o , for spraying cold water or other cooling liquid over it.

Having now described the various apparatus employed, and having explained their operation, it remains to give a short description of the operation of the system as a whole.

Reference will be made principally to Fig. 21, which is lettered, as far as possible, to correspond with the other figures. The dotted arrows indicate the flow of gases. The solid arrows indicate the flow of liquid, except the feathered arrow in the lower right-hand corner, which indicates the passage of solid carbonate of sodium.

Assuming that the brine to be treated is one containing ammonia, with impurities of iron compounds and earthy chlorides, the said brine, as it comes from the springs or wells, is treated with a small quantity of lime, sufficient to precipitate the iron, and a small quantity of magnesia. This crude or slightly-purified brine is pumped into the tank U, from which the other apparatus are supplied. The brine to be evaporated for salt is run by the pipe 100 into the lime-tank W, wherein it is mixed with milk of lime from the mixer W' and run into a still Y, and the ammonia being driven off is collected and conveyed through the condenser Y' and pipe 101 to the saturator, (indicated at B².) The brine is then pumped into the grainers, which are heated by the kiln-gases on their way to the carbonating or precipitating apparatus. The gases from the kiln F (shown in detail in Figs. 9, 10, and 11) are by the compressor F¹⁵ forced through the heating-coil 102 of the grainer, and thence pass by the pipe g^o into the condenser-column G, (shown in detail in Fig. 12,) wherein they are cooled and washed by water from the tank 103, which water is introduced by the pipe g and runs away by the pipe H^o. The gases enter the carbonator D (see Figs. 6, 8) by way of the pipes g' d^o. The brine for soda-making is run from the supply-tank U into a tank, 104, where it is mixed with magnesium carbonate, preferably with the freshly-precipitated carbonate from the filter-press. The quantity of magnesium carbonate used is that required to de-

compose the calcium chloride in the brine. From the mixing-tank 104 the liquid runs into a settling-tank, 105. After settling for, say, twenty-four hours, the clear liquor is decanted into a mixing-tank, 106, where it is mixed with sodium carbonate in quantity sufficient to decompose the magnesium chloride and a slight excess, and is then run into a filter-press, 107, of ordinary or suitable construction, or into a centrifugal filter or other apparatus for filtering under pressure. In this press magnesium carbonate is retained and the clear bright brine is run off. The magnesium carbonate contains not only the natural magnesium of the brine, but the quantity added to precipitate the calcium. It can be sold or utilized in any desirable way. There are two mixing-tanks, 104, two settling-tanks, 105, and two mixing-tanks, 106. They are connected by pipes arranged, as indicated in the diagram, (the pipes being provided with cocks,) so that either of the settling-tanks 105 may receive the contents of either of the tanks 104 and 106, and so that the contents of either of the latter may be run into the filter-press 107. The tanks 104 and 106 and the lime-mixer W' are or may be constructed like the lime-mixer S' (see Fig. 19) and the lime-tank W like that represented by S, Fig. 19. The clear purified brine is pumped into the supply-tank 108, whence it is supplied to the different apparatus. About ninety per cent. is run through the pipe a^o, the column tanks A A' A², Fig. 1, where it takes up ammonia from the gases that escape from the carbonating or precipitating apparatus, Fig. 6, and enter the column-tanks by way of the pipe a'. From the column-tanks it is pumped into the tank which supplies the saturator. It passes successively through the saturator-column B³ and saturator B², Fig. 2, and the salt-column C, Fig. 5, into the averaging-tanks 109. The remaining ten per cent. of the purified brine is used in the square tower 110 to wash and recover ammonia from the gases which pass from the carbonating or precipitating apparatus D through the column-tanks A² A' A, and enter the base of said tower by the pipe a². The wash-brine is pumped up through the pipe 111 into the supply-tank 112, whence it is delivered by the pipes 113 and 114, and is pumped into the ammoniated brine from the saturator in its averaging tanks 109. In case the whole of the wash-brine is not required for diluting the ammoniated brine from the saturator, the excess is delivered by the pipes 113 and 115 into the brine from the column tank A² on its way to the saturator-column. Should the wash-brine be insufficient in quantity for the purpose named, fresh brine from the supply-tank is added to the ammoniated brine, the said fresh brine being carried by the pipes 115 and 114 around the saturator-column B³, saturator B², and salt-column C, and delivered into the averaging-tanks 109. At 116 one or more cocks are placed, so that either of the pipes 114 and

115 may be connected with the pipe 113, and so that they may also, when desired, be connected with each other. By turning the proper cocks the delivery of wash-brine or of fresh 5 brine into the ammoniated brine can be regulated.

From the averaging tanks the brine is pumped through the pipe d^2 into the carbonating or precipitating apparatus D, Fig. 6, 10 where it meets the carbonic acid from the lime-kiln, Fig. 9, after passing through the compressor, the grainers, and the condenser, Fig. 12, and also the carbonic acid from the roaster M', Fig. 16, after passing through the dust-trap 15 N, Fig. 16, a compressor, 117, and a surface-condenser, 118.

The gases from the carbonating or precipitating apparatus pass, as already stated, to and through the column-tanks, Fig. 1, and the square tower. From the carbonating 20 or precipitating apparatus the ammonium-chloride solution, holding the precipitated bicarbonate of soda in suspension, flows into the filter K*, Fig. 13, wherein the said solution is separated from the bicarbonate, and the latter is washed. The air drawn from the tank below the filter-belt through the pipe k^2 into the aspirator and compressor K³ is by the latter forced into the iron-tower 119, where it is washed with water supplied from the tank 103 25 by the pipe 121. The wash-liquid is delivered through the pipe 122 into the ammonium-chloride solution from the filter K, having run through the pipe k^2 , and its branches into the spider-tank 120, and thence into the receiving- 30 tank 124, is from the latter pumped or forced by steam acting upon the surface of the liquid, as in a monte-jus, into the tank 123. The waste gases from the saturator-column B⁵ are conducted by the pipe b^8 into the pipe-tower B⁶, 35 where they are washed with water, which is run from the water-tank 125 into the top of the said tower. The waste water is delivered into the ammonium-chloride tank 123 through the pipe b^9 . The dust-trap is supplied with water 40 from the tank 103 by the pipe n^4 . The overflow by the pipe n^5 and the water of condensation from the surface-condenser 118 are delivered by the pipe 126 into the tank 123. These ammoniated liquors are run from the tank 45 123, through the pipe 129, condenser-column Q², pipe u^3 , lime tank S, pipe q^4 , still-columns Q Q', into the boilers R R'. The ammonia expelled from the solution in the still-columns and boiler, together with other vapors, pass by 50 pipe q^8 into condenser-column Q³, and thence into condenser Q³. The cooled ammonia from the condenser unites with the ammonia from still Y, and by pipe 101 is delivered into the saturator. The calcium-chloride solution 55 which collects in the boilers R R' is blown off from time to time. From the filter K* the bicarbonate of soda is delivered by the belt-conveyer L² into the roaster M', Fig. 16, wherein the extra equivalent of carbonic acid, together 60 with the ammonia and moisture, are driven off, the said gases passing, as already stated, through the dust-trap N, compressor 117, and

surface-condenser 118 to the carbonating or precipitating apparatus D. The sodium carbonate from the roaster is, by the elevator P² 70 and jacketed conveyer P, (shown in Fig. 18,) conveyed to a packing-machine, 127, and is cooled in its passage.

The calcium-chloride solution which is blown off from the still, Fig. 19, is allowed to 75 run to waste, or it can be utilized in any known and suitable way.

The pipes connected with each boiler are placed centrally on the boiler, one behind the other. In Fig. 19 their position is altered, so 80 that they all can be seen.

Modifications can be made in the details without departing from the spirit of the invention, and parts of the invention can be used without the others. For example, as follows: 85

Instead of using compressors and aspirators operating by means of steam jets on the principle of the injector for compressing the carbonic acid and for creating a vacuum in the pipe-tower and in the filter-tank, pumps 90 or other means of compression and aspiration could be used. The steam-jet devices have, however, special advantages in the connection in which they are employed, and their use in such connection of them in contradistinction 95 to other compressors and aspirators forms a part of the invention.

Instead of using the brine for soda making as a wash-liquid to recover the ammonia, water could be employed, the wash-water to be 100 afterward distilled; but it is obvious that in such cases the advantages attending the use of the brine for the purpose would be lost. Certain of the apparatus might be used for other purposes than that which is indicated, 105 and certain parts only of a particular apparatus might be employed.

In the saturator other than scoop-shaped paddles could be used, although it is believed that the scoop-paddles are best adapted to the 110 purpose. A similar remark applies to the roaster, only in that case, owing to the peculiar nature of the material to be roasted, there are greater difficulties in the way of a change. The zigzag arrangement of flues 115 shown in Fig. 8 could be adopted in the saturator and roaster, as well as in the carbonating or precipitating apparatus. The brine could be passed through the salt-column after instead of before the brine is corrected for ammonia. 120

The saturator could be used to absorb ammonia obtained from any available source, or it might be used for other purposes, and so of other apparatus. One or more of the apparatus could be substituted for corresponding apparatus in existing systems with improvement to the latter; but it is obvious in such case a part only of the invention would be employed. 125

Many other changes and modifications could be indicated; but it is believed to be unnecessary, what has been described being considered the best mode of carrying the invention 130

and every part thereof into effect. The term "brine" is used as of same meaning as sodium-chloride solution, and as indicating as well an artificial as a natural brine, and as well a pure solution as a solution requiring to be purified.

I am aware that heretofore natural brine has been mixed with lime and treated with ammonia or ammonium carbonate, and has afterward been filtered under pressure to effect the separation of the precipitated lime and magnesium carbonates. Such process is not included in the present invention.

I am also aware that in making sulphite solutions the uncompRESSED sulphurous-acid gas has been mixed with the absorbing liquid by means of rotating buckets which carry the gas down into the liquid and there discharge it. Such a process or apparatus is not included in the invention.

I am further aware of an apparatus for vaporizing hydrocarbons, in which the oil to be vaporized flows over the outside of a column composed of spheroidal receivers, through the interior of which steam is passed. This apparatus, also, is not within the invention.

I claim the new improvements herein described, all and several, to wit:

1. The method of purifying brine from earthy chlorides by precipitating the earthy bases and separating the same by filtration under pressure, substantially as described.

2. In the purification of brine, the separate and successive precipitation of the earthy bases, the calcium with magnesium carbonate and the magnesium with sodium carbonate, substantially as described.

3. The method of purifying brine by precipitating the calcium with magnesium carbonate and afterward precipitating the magnesium with sodium carbonate and filtering under pressure, substantially as described.

4. In the ammonia-soda manufacture, the purification of the brine by precipitation of impurities and filtration under pressure, and subsequent treatment of the brine so purified with ammonia and carbonic acid, substantially as described.

5. In the ammonia-soda manufacture, the purification of the brine by precipitation first of the calcium by magnesium carbonate and then of the magnesium by sodium carbonate, and the treatment of the brine so purified with ammonia and carbonic acid, substantially as described.

6. In the ammonia-soda manufacture, the continuous saturation of the brine with ammonia by beating the brine into a spray in one or more elongated vessels or tubes containing an atmosphere of ammonia, a continuous flow of the brine and of the ammonia being maintained through the said vessels, substantially as described.

7. The method of subjecting a liquid, such as the brine, to the action of a gas, such as ammonia, by maintaining a column of the liquid, causing the liquid to flow therefrom

through one or more tubes, maintaining a current of the gas in the opposite direction through the tubes, bringing the liquid and gas into intimate contact in their passage, and finally passing the gas through the column of liquid, substantially as described.

8. In the ammonia-soda manufacture, restoring the strength of the solution in sodium chloride after saturation with ammonia by causing it to flow or percolate through a mass or column of solid salt, substantially as described.

9. In the ammonia-soda manufacture, super-ammoniating the brine and afterward reducing the strength by addition of other brine, substantially as described.

10. In the ammonia-soda manufacture, the improvement consisting in utilizing a portion of the brine to recover the ammonia from waste gases, saturating the large body of the brine with ammonia in excess, and reducing the strength of the superammoniated brine with the wash-brine, substantially as described.

11. In the ammonia-soda manufacture, causing a continuous flow of the superammoniated brine and of the diluting brine, and regulating the proportionate delivery of the two brines without interrupting the continuity of flow, substantially as described.

12. The method of preparing the ammoniated brine by saturating the brine with ammonia, restoring the salt strength, and correcting the excess of ammonia, all in a continuous manner, substantially as described.

13. In the ammonia-soda manufacture, the improvement consisting in maintaining a body of compressed carbonic acid above a body of ammoniated brine and causing repeated contacts between the two by means of revolving buckets, which carry the compressed carbonic acid below the surface of the ammoniated brine and there discharge it, so that it may rise through said brine, substantially as described.

14. In the ammonia-soda manufacture, the improvement consisting in effecting repeated contacts between the ammoniated brine and compressed carbonic acid by mechanical appliances, causing the waste gases from that operation to bubble through a column of fresh brine, and subsequently ammoniating and carbonating such fresh brine, the said column of fresh brine not only recovering ammonia and carbonic acid from the waste gases, but also maintaining under pressure the carbonic acid in the carbonator or precipitating apparatus, substantially as described.

15. In the ammonia-soda manufacture, the improvement consisting in burning lime with hydrocarbon oil or similar clean fluid fuel and treating the ammoniated brine with the gases from the decomposition of the lime and the combustion of the fuel, substantially as described.

16. In the ammonia-soda manufacture, the separation of the precipitated bicarbonate of soda from the ammonium-chloride solution by

- running a stream of the liquid holding bicarbonate in suspension upon a moving filter-cloth and removing the bicarbonate therefrom continuously, substantially as described.
- 5 17. In the ammonia-soda manufacture, the filtration of the ammonium-chloride solution from the bicarbonate of soda, the washing of the bicarbonate and filtration of the wash-liquid therefrom, all in a continuous manner, by receiving the stream of liquid holding the bicarbonate in suspension upon a moving filter-cloth and carrying the separated material under a jet of wash-liquid, substantially as described.
- 15 18. In roasting bicarbonate of soda, the separation of the fine dust from the gases expelled from the roaster by passing said gases through a liquid, substantially as described.
- 20 19. In the ammonia-soda manufacture, the improvement consisting in continuously filtering the liquid after precipitation of the soda as bicarbonate and washing and roasting the precipitate also in a continuous manner, a continuous flow or progression of the material under treatment being maintained through the filter and the roasting apparatus and from the former into the latter, substantially as described.
- 25 20. In the ammonia-soda manufacture, the improvement consisting in continuously saturating the brine with ammonia, continuously precipitating bicarbonate of soda with carbonic acid, continuously filtering the liquid to separate the precipitate, and continuously roasting the precipitate, a continuous flow or progression of the material under treatment being maintained through the saturator, carbonator, filter, and roasting apparatus, substantially as described.
- 30 21. In the ammonia-soda manufacture, the improvement in washing the precipitated bicarbonate of soda, consisting in spraying with an atomizer the wash-liquor over the said bicarbonate while it rests upon a filter-cloth or porous fabric and maintaining a vacuum under said cloth or fabric, substantially as described.
- 35 22. In the ammonia-soda manufacture, the improvement consisting in continuously saturating the brine with ammonia, continuously generating carbonic acid and treating the ammoniated brine therewith, continuously filtering the liquid to separate the bicarbonate of soda, continuously roasting the said bicarbonate and utilizing the carbonic acid expelled, and finally distilling the ammonia from the ammonium-chloride solution and utilizing it to saturate the fresh brine, a continuous flow or progression of the treating agents and the material under treatment being maintained through the saturator, carbonator, filter, roasting apparatus, and still, substantially as described.
- 40 23. In the ammonia-soda manufacture, the simultaneous conveying and cooling of the stream of sodium carbonate from the roaster, substantially as described.
- 45 24. The saturator comprising, in combination, the tubes, the gas inlet and outlet, the liquid inlet and outlet, and the conveying and agitating devices in said tubes, substantially as described.
- 50 25. The combination, with a tube, of an internal shaft, and scoop-paddles and conveyer flights fixed on said shaft, substantially as described with reference to the saturator and roaster.
- 55 26. The combination, in an apparatus such as the saturator or carbonator, of the tubes, means, as indicated, for effecting the intimate contact of the gas and liquid in said tubes, and means for circulating a cooling medium over said tubes, substantially as described.
- 60 27. The combination, with the saturator comprising tubes and agitating devices therein, of the saturator-column, substantially as described.
- 65 28. The combination of the saturator, wash-tower, and aspirator for making a vacuum in said tower, substantially as described.
- 70 29. The combination of the saturator, saturator-column, wash-tower, and aspirator, substantially as described.
- 75 30. The combination of the ammonia-still, the saturator, the wash-tower, and aspirator, substantially as described.
- 80 31. The salt-column comprising the receiving-vessel, the valve for introducing the salt, and the liquid inlet and outlet, substantially as described.
- 85 32. The combination of the saturator and salt-column with means for conveying the ammoniated brine from the saturator through the salt-column, substantially as described.
- 90 33. The combination of the saturator, averaging-tanks, pipes connecting the liquid-outlet of the saturator with said tanks for conveying the ammoniated brine into said tanks, and means for adding the diluting brine to that from the saturator, substantially as described.
- 95 34. The combination of the saturator, salt-column, pipe connecting the liquid-outlet of the saturator with the salt-column, and means for adding diluting brine to that from the saturator, substantially as described.
- 100 35. The carbonating or precipitating apparatus comprising a horizontal vessel or series of vessels provided on the inside with revolving buckets, a compressor for forcing carbonic acid under pressure into said vessel or vessels, and a column of liquid through which the carbonic acid escapes for maintaining the pressure in said vessel or vessels, substantially as described.
- 105 36. The combination of the column-tanks and the carbonating or precipitating apparatus, the gas outlet of the latter being connected with the gas-inlet of the lowermost column-tank, substantially as described.
- 110 37. The combination of the column-tanks, the saturator, and the carbonating or precipitating apparatus, with means for delivering the gases from the carbonating or precipi-

tating apparatus into the column-tanks and the liquid from the column-tanks into the saturator, substantially as described.

38. The combination of a limekiln, means for collecting the carbonic acid generated, the carbonating or precipitating apparatus, the compressor for forcing the carbonic acid into said apparatus, and the grainers having their heating-flues arranged between the limekiln and the said apparatus, substantially as described.

39. The apparatus for cooling and dehydrating the compressed carbonic acid, said apparatus comprising a column with perforated diaphragm and other appendages, and a trap having unequal legs and arranged to permit the discharge of the liquid, while maintaining the pressure, substantially as described.

40. The combination, with a vessel and the liquid-outlet therefrom, of a U-trap having unequal legs, and provided with a faucet or cock in the longer leg at or about the level of the said outlet, said longer leg extending above the said level, substantially as described.

41. The combination, with the carbonator or precipitating apparatus, of the carbonic-acid generator for burning limestone with hydrocarbon oil or similar clean fluid fuel, and the compressor for forcing the carbonic acid generated into said apparatus, said limekiln being provided with pipes for delivering the fluid fuel at the base of the shaft, with valves for regulating the supply of fuel and air, and with fuel for carrying off the carbonic acid, substantially as described.

42. The combination of the carbonic-acid generator or limekiln burning fluid fuel, the compressor, the grainers, the condenser-column and trap, and the carbonating or precipitating apparatus, substantially as described.

43. The combination of the filter-tank, an aspirator and compressor, and a wash tower, substantially as described.

44. The combination, with the continuously-operating carbonator or precipitating apparatus, of the continuous filter, substantially as described.

45. The combination, with the wash-tower for washing the air exhausted from the filter-tank, of conveying pipes and vessels for mixing the wash-brine with the other brine to be treated for conversion of the sodium chloride into sodium carbonate, substantially as described.

46. The combination, with the continuous filter having a revolving horizontal filter cloth or belt, of the roaster, also operating continuously, and the mechanical conveyer for delivering the bicarbonate from the filter to the roaster, substantially as described.

47. The combination, with the flues of the roaster and means for heating the same, of the shafts with series of detached or disconnected paddles and conveyer-flights, substantially as described.

48. The combination of the furnace, the flues set therein so as to be heated by the fire heat

or products of combustion, the shafts in the flues, and the scoop-shaped paddles and conveyer-flights on said shafts, substantially as described.

49. The combination, with the heated flues and the conveying and agitating devices therein, of the loaded flaps or valves for excluding air while admitting the introduction and discharge of the material, substantially as described.

50. The combination, with the roaster, of the dust-trap, substantially as described.

51. The combination, with the roaster and the compressor, of the dust-trap interposed between them, substantially as described.

52. The combination of the roaster, the compressor, the surface-condenser, and the carbonating or precipitating apparatus, substantially as described.

53. The combination of the carbonating or precipitating apparatus, the continuous filter, the roaster, and the compressor for forcing the carbonic acid from the roaster into the carbonating or precipitating apparatus, substantially as described.

54. The combination, with the saturator, the carbonating or precipitating apparatus, filter, and roaster, all operating continuously, of the column-tanks, the wash-towers, and the connecting-pipes, pumps, conveyers, aspirators, and compressors, substantially as described.

55. The combination of the saturator, the carbonating or precipitating apparatus, the limekiln, the filter, the roaster, the still, the column-tanks, the wash-towers, the grainers, the condensers, the connecting-pipes, the pumps, the conveyers, the aspirators, the compressors, and the several tanks, all connected and adapted for continuous operation, substantially as described.

56. The combination, with the roaster, of the conveying and cooling apparatus, substantially as described.

57. The combination, with the still proper, of the lime-tank for supplying milk of lime to mix with the ammoniacal liquors, substantially as described.

58. The combination, with the still proper, of the condenser-column and the lime-tank adapted to supply milk of lime, arranged substantially as described.

59. The combination of the condenser-column, the lime-tank, the mixing apparatus, and the still proper, substantially as described.

60. In a still, the hollow column formed of a number of semispherical communicating vessels, substantially as described.

61. The combination of the hollow column formed of hemispherical vessels and the frustoconical drip-plates, substantially as described.

62. The combination, with the boilers, of the pipes and cocks arranged substantially as described—that is to say, the steam-pipe, its branches and cocks, the liquid-pipe for conveying the solution from the still-column to the boilers, its branches and cocks, and the vapor-pipe for conveying the steam and other vapors

from the boilers to the still, its branches and cocks.

63. The combination, with one or more boilers, of the still-columns, having each an irregular hollow column communicating with the exterior shell at the bottom and connected as follows: the steam-outlet from the boilers with the upper part of the hollow column in the lower still-column, and the steam and vapor outlet from this column with the top of the hollow column in the next still-column, substantially as described.

64. In an apparatus such as the carbonating or precipitating apparatus, the combination

of the precipitating vessels or tubes, the overflow-pipes, and the stirrers in said pipes, substantially as described.

65. The combination, with the carbonating or precipitating apparatus, of the trap provided with stirrers and adapted to maintain the pressure in said apparatus, substantially as described.

In testimony whereof I affix my signature in presence of two witnesses.

HERMAN FRASCH.
